Primary Examiner — Shannon W Morgan*Assistant Examiner* — Kellianne M Shaver(74) Attorney, Agent, or Firm — Gottlieb, Rackman & Reisman, PC(57) CLAIM

The ornamental design for a bowl, as shown and described.

DESCRIPTION

FIG. 1 is a front perspective view of a bowl illustrating my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in FIG. 7 illustrate portions of the bowl and form no part of the claimed design.

1 Claim, 7 Drawing Sheets(56)
